CLAIM

The ornamental design for a griddle caddy as shown and described.

DESCRIPTION

FIG. 1 is a perspective view of a griddle caddy showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an exploded perspective view of the griddle caddy. The broken lines in the drawings depict portions of the griddle caddy that form no part of the claimed design.

1 Claim, 9 Drawing Sheets
